UNITED STATES PATENT OFFICE.

WILLIAM WOOD, OF BIRKENHEAD, ENGLAND.

PUNCHING AND THE LIKE MACHINE.

1,296,895.

Specification of Letters Patent. Patented Mar. 11, 1919.

Application filed July 20, 1917. Serial No. 181,877.

To all whom it may concern:

Be it known that I, WILLIAM WOOD, a subject of the King of Great Britain, and residing in Birkenhead, in the county of 5 Chester, England, have invented certain new and useful Improvements in Punching and the like Machines, of which the following is a specification.

This invention relates to machines for 10 perforating metal plates and is particularly applicable to machines for punching the rivet holes in ships' plates, and has for its object the improvement of such machines so as to render them suitable for automatically 15 perforating holes in plates, the longitudinal disposition of the centers of which, instead of being in right lines are in lines of curved contour to suit the shear of the ship, so that between successive perforations the plate re- 20 quires to be moved through varying distances transversely as well as to be moved longitudinally.

The invention, as applied to a multiple 25 punching machine, is illustrated in the accompanying drawings in which:—Figure 1 is an elevation of the central portion of the machine, the respective extensions to the right of the line R, R, and to the left of the line L, L, being shown in Figs. 1^R and 1^L.

Fig. 2 is a plan view of the machine to a 30 reduced scale.

Fig. 3 is a fragmentary view, to an enlarged scale, of part of Fig. 2 and shows the hauling carriage; Fig. 4 being a similar 35 view to Fig. 3, but showing the trailing carriage.

Fig. 5 is an elevation in transverse section on the line V, V, of Fig. 3.

Figs. 6 and 7 are respectively, an elevation 40 and an elevation in section on the line VII, VII, of Fig. 3; Fig. 8 is a transverse section on the line VIII, VIII, of Fig. 6; and Fig. 6^A is a fragmentary end view of a part of Fig. 6.

Fig. 9 is an elevation viewed in the opposite direction to Fig. 1; and Fig. 10 is a corresponding plan; Figs. 11, 12 and 13 are fragmentary views partly in section, of details shown in Figs. 9 and 10, and Fig. 14 is 50 a fragmentary view of a modification.

Throughout the drawings the same parts

are indicated by the same letters or figures of reference, and in the case of sections the directions in which they are viewed are indicated by the small arrows placed adjacently 55 to the lines denoting the plane of section.

A is the cross frame of the machine and it carries a series of punches P carried in a suitably guided cross girder p¹ reciprocated by eccentrics p², and eccentric sheaf frame 60 p³; the eccentrics are mounted on a cross shaft a¹ which is driven by the spur wheel a² gearing with the pinion a³ on the shaft a⁴ (see Fig. 9) which is in turn driven by the spur wheel a⁵ (see Fig. 1) gearing with the 65 pinion a⁶ secured to the fly-wheel a⁷ and belt pulley a⁸ which is driven by any suitable means, say, an electric motor a⁹.

The several punches are each fitted with an interposing plate p⁴ which when pushed 70 in renders the punch operative, but which when withdrawn, as in Fig. 13, leaves the punch free to rise and fall without punching.

B is the guide bed of the machine carried from the frame A and feet b¹, and C is the 75 traversing screw driven by speed change wheels c¹ (Fig. 10), from the lay shaft c² geared by the bevels c³ to the shaft c⁴ to which shaft is imparted an intermittent angular movement in the one direction by a 80 pinion c⁵ through a "free wheel" pawl c⁶, carried by the pinion and engaging with the tooth C on the interior of the brake block c⁷, which block is provided with a claw coupling c¹⁵ by which it can be coupled to the 85 shaft by a sliding clutch c¹⁰, the pinion c⁵ being driven by the quadrant c⁷ which is reciprocated by the rod c⁸ connected to the crank pin a⁹; a claw disengaging clutch c¹⁰ and shifting-lever c¹¹ is fitted and the shaft 90 c⁴ is prevented from rotating in the reverse direction, when the pinion rotation is reversed, by the brake band c¹² coiled around the brake block c¹³ and fitted with a weight c¹⁴. K is the presser plate. 95

The arrangements described are common to punching machines of this type and are illustrated to show the coöperation of perforating means and the traversing means with features of the invention described below, and need not further be described. They are given by way of example and it is to be 100

understood that any suitable organization for perforating the plates either by drilling or punching, and any suitable organization for imparting intermittent angular movement to the feed screw may be employed.

D is the hauling carriage, and E is the trailing carriage, and the plate F, to be perforated is attached, at the leading end, to a part traveling longitudinally with the hauling carriage but capable of transverse movement relatively thereto, and at the trailing end to a part traveling longitudinally with the trailing carriage and capable of transverse movement relatively thereto, and these 10 two parts are guided by means of longitudinally disposed flexible guide-ways fitted with adjusting means whereby they may be made to conform to the desired curvature requisite to impart to the said two parts, as 15 they are moved longitudinally, the necessary 20 transverse movement.

In the arrangement illustrated, the leading end of the plate F is attached by the pinching screw d^1 to the jaw-bracket d^2 25 (Fig. 6) which in turn is threaded on to the sliding bar G and secured in position thereon by the pinching screw d^4 . The bar G is slidably mounted in jaw extensions d^5 of the pivoted part D' of the hauling carriage.

The pivoted part D' is connected to the adjustable part D'' of the hauling carriage D by the pivot pin d^6 and is provided with runners d^7 which support the weight and 35 run on the machined surfaces of the bed B, and is maintained in correct transverse alignment by depending portions d^{11} fitting between the inner edges of the rails of the guide bed. The sliding bar G is guided in 40 the jaw extensions d^5 by anti-friction rollers d^8 against which the bar presses when the plate is being hauled along; the jaw bracket d^2 is provided with a runner d^9 which bears on the horizontal web d^{10} of the part D' 45 (see Figs. 6 and 7). The hauling carriage D is fitted with runners d^{12} which run on guide rails, being maintained in transverse alignment by the depending portion d^{13} (see Figs. 7 and 8).

50 The hauling carriage D (see Figs. 6, 7 and 8) is fitted with any suitable form of nut d^{14} adapted to engage with or to be disengaged from the traversing screw C; in the arrangement illustrated, which for 55 the sake of simplicity is more or less diagrammatic, the nut d^{14} is carried on the end of a screw d^{15} so that the latter can rotate relatively thereto, the nut d^{14} being prevented from rotating on the screw by a pin d^{16} ; when the screw d^{15} is rotated by a handle d^{17} axial movement is imparted to the nut, causing it to either engage or disengage as may be desired. The adjustable part D'' of the hauling carriage is adapted

to have limited longitudinal movement relatively to the part D, and longitudinal adjustment between the carriage D and the adjustable part D'' and the pivoted part D' connected thereto is obtained by means of the screw d^{18} which is journaled in the bracket d^{19} carried from the hauling carriage D and which screws into the bracket d^{20} carried from the adjustable part D''; the fine adjustment of the plate axially in relation to the punches is thus obtained, 75 after which the two parts D'' and D of the hauling carriage may be secured together by the bolts d^{21} .

It may be necessary, in the case of an exceptionally long plate, to attach it to the hauling carriage at an intermediate point, and for this purpose an angle bracket d^{22} is bolted to the vertical extension d^3 of the jaw bracket d^2 .

The trailing carriage E is adapted to slide 85 along the guide bed B, and the rear of the plate is attached to the jaw bracket e^2 by the pinching screw e^1 , the jaw bracket being threaded on the bar G' and being fixed in position thereon by the pinching screw e^4 . The bar G' is carried in the jaw extensions e^5 of the pivoted part E' connected to the trailing carriage E by the pivot pin e' , the sliding bar being guided in the jaws by the antifriction rollers e^8 .

It will be seen that the construction of the trailing carriage resembles that of the hauling carriage, with the exception that it is not necessary to provide it with an adjustable portion such as D'' nor with a nut 100 for connecting it to the traversing screw; it may, however, be provided with runners similar to d^{12} shown on D, and the jaw bracket e^2 may have a runner such as d^9 running on a web on E', such as d^{10} shown 105 in connection with the hauling carriage.

Motion is imparted to the transversely moving portions of the hauling and trailing carriages respectively by guide tracks H and H' . According to one modification 110 (see Figs. 1, 3, 4 and 5) the tracks may consist of two rails h secured together by distance pieces h^1 and fitted with a series of adjusting screws h^2 located at suitable intervals; the screws h^2 are carried at their outer 115 ends by the framework h^3 fitted with spherical seatings h^4 against which the end locking nuts h^5 bear; the inner ends of the screws are carried in slotted brackets h^6 and are fitted with spherical collars h^7 120 which locate them axially; the adjusting screws pass through the nuts h^8 carried non-rotatably between the rails, and it will be seen that if the screws h^2 be rotated by the handle h^9 , the rails, which are reasonably 125 flexible, may be curved to such contours as correspond with the shear lines of ships' plates.

The sliding bars G and G' are fitted with a roller g^1 which fits between the rails h . The bearing wheels M which support the plate so as to facilitate its longitudinal movement, are arranged on their spindles so as to have considerable axial adjustment in order that they may be located clear of the guide rails in accordance with the position of the latter which of course varies 10 in accordance with the shear and length of the plates.

Assuming that the machine is required to punch a ship's plate having a given shear, then the guide rails would be set by means 15 of the screws h^2 to the required contour in any convenient manner; usually one side of the guide bed B would be taken as the base line, and the guide rails would be manipulated by the screws h^2 so that the distance 20 from the said base at ordinates spaced, say, to agree with the frame spacing of the ship would correspond with the shear heights taken from the scribe board for the particular plate, the corresponding ordinates on 25 opposite sides of the line of punching being properly located in respect to the said line in accordance with the length of the plate to be punched; the contour of the two guides H and H' would normally be similar curves, 30 and it will be seen, as the plate is connected at the one end to the sliding bar G and at the other end to the sliding bar G', that as the hauling carriage and the trailing carriage are drawn along longitudinally as the 35 punching proceeds, each end of the plate is moved transversely across the machine by the same amount and in accordance with the shear line. The contour of the guides H and H' need not, however, be similar, and by selecting suitable contours for the respective 40 guides, plates to be located, for example, near the ends of a ship where the lines of holes of successive frames are not parallel, may be automatically punched.

45 In the modification illustrated in Fig. 14, a single guide rail H'' is employed instead of the double rails previously described; the construction of the adjusting screws may be the same as before, but the nuts h^{10} through 50 which they pass are secured to the single rail, and instead of single roller such as g^1 on the ends of the bars G and G', the said bars are each fitted with a collar g^2 the stem g^3 of which passes through the bar and to 55 the underside of which are fitted double rollers which respectively embrace opposite sides of the rail H''.

The guides H and H' may be duplicated, 60 one of each being placed on each side of the machine, corresponding guiding means being provided on each end of the sliding bar G. When the machine is required to be used in the ordinary way without the guiding surfaces, the sliding bars may be turned

through 180° so as to free the engaging 65 means from the guiding surfaces.

In order to adapt the machine to deal with plates longer than the length of the guide bed provided with a guide screw, the hauling carriage may, in the first instance, be 70 attached to the leading edge of the plate and the rear of the plate is carried over the trailing carriage, the latter being attached to the plate some distance in front of the rear edge. When the plate carried in this way has been 75 perforated as far as practicable, the trailing carriage is detached, moved rearwardly and attached to the rear of the plate, the hauling carriage also being detached, passed rearwardly under the plate and secured to it at 80 a point a corresponding distance in rear of the front edge. In order to guide the hauling and trailing carriages over the rest of the forward movement of the plate, auxiliary guides H^a and H^b, as shown in Fig. 2, 85 are provided, the opposite ends of the sliding bars G being arranged to engage with them and their curvature being so arranged that the plate is given the same transverse movement as would have been obtained had 90 it been possible to continue the guide surfaces H, H'.

Having now fully described my invention, I declare that what I claim, and desire to secure by Letters Patent is:—

1. In a machine for perforating plates, the combination of perforating means, carrier means at each end of the plate to be punched, driving means to move the carriers longitudinally to thereby move the plate in 100 respect to the punch, said carrier means being also adapted to have transverse movement, and two guides, one at each end of the plate for controlling the transverse movement of the carriers, substantially as described.

2. In a machine for perforating plates, the combination of perforating means, carrier means at each end of the plate to be punched, driving means to move the carriers longitudinally to thereby move the plate in 110 respect to the punch, said carrier means being also adapted to have transverse movement, two guides, one at each end of the plate for controlling the transverse movement of the carrier, each of said guides being flexible, and means for flexing each of said guides for changing the contour thereof.

3. In a machine for perforating metal plates in combination, a hauling carriage, a 120 trailing carriage; longitudinal guides for said carriages; plate-attachment means carried by the hauling carriage and movable transversely relatively thereto; plate attachment means carried by the trailing carriage 125 and movable transversely relatively thereto; means adapted to impart intermittent movement to the hauling carriage; an adjust-

able guide adapted to take a curvilinear contour and to impart transverse movement to the plate attachment means as the plate moves longitudinally; means for adjusting 5 the contour of the guide; means adapted to perforate the plate in the intervals between the said intermittent movements of the plate; and driving means adapted to actuate said means in coöperation; substantially 10 as described.

4. In a machine for perforating plates and in combination with means for perforating the plate, means for intermittently moving the plate longitudinally through the machine and driving means for operating the said means in coöordination,—a flexible guide surface provided at intervals with nuts to take transversely arranged screws, and a series of transversely arranged screws held 15 against axial movement and adapted by rotation in the nut to adjust the contour of the flexible guide surface; substantially as described.

5. In a punching machine, in combination 25 with means for punching the plate; a hauling carriage; a trailing carriage; means for guiding the said carriages longitudinally through the machine; means for imparting intermittent longitudinal movement to the hauling carriage between the punching operations; driving gear for operating the said two means in coöordination; adjustable guides adapted to take curvilinear contours; means 30 for adjusting the contour of the guides; a part carried by the hauling carriage transversely movable relatively thereto and fitted with plate attachment means; a part carried by the trailing carriage transversely movable relatively thereto and fitted with plate 35 attachment means; said two moving parts being fitted with means adapted to engage with the respective adjustable guides and to move the said parts and the plate transversely as the plate is moved longitudinally; 40 substantially as described.

6. In a punching machine, in combination: means for punching the plate; a traversing screw; means for imparting intermittent rotary movement to the traversing screw 45 between the punching operations; driving means for operating the said means in coöordination; a hauling carriage adapted to be moved longitudinally by the said screw; a trailing carriage; means for guiding said 50 carriages longitudinally through the machine; adjustable guides adapted to take curvilinear contours; means for adjusting the contour of the guides; a part carried by the hauling carriage transversely movable 55 relatively thereto and fitted with plate attachment means; a part carried by the trailing carriage transversely movable relatively thereto and fitted with plate attachment 60 means; said two moving parts being fitted

with means adapted to engage with the respective adjustable guides and to move the said parts and the plate transversely as the plate is moved longitudinally; substantially as described.

7. In a punching machine, in combination 70 with means for punching the plate, an intermittently operated traversing screw for moving the plate longitudinally, driving means and guide surfaces,—a hauling carriage having a pivoted part; a trailing carriage having a pivoted part; transverse moving parts engaging with the guides and carrying the plate attachment parts and being mounted respectively on the pivoted parts of the said carriages; substantially as 75 described.

8. In a punching machine, in combination with means for punching the plate,—means for traversing the plate, driving means, guide surfaces, a hauling carriage having a pivoted part, a trailing carriage having a pivoted part, transversely moving parts carried by the said pivoted parts of the carriages engaging with the guides and carrying the plate attachment means, and respectively slidably carried in the pivoted parts of the carriages; substantially as 80 described.

9. In a punching machine, in combination with means for punching the plate:—a traversing screw, means for imparting intermittent movement to the traversing screw and operating the punching means, guide surfaces, hauling and trailing carriages having plate attachment means slidably carried thereby and engaging with the respective guides, means on the hauling carriage adapted to engage with the traversing screw, and means for adjusting the plate attachment means of the hauling carriage longitudinally relatively to the said engaging means; substantially as described.

10. In a machine for perforating plates and in combination with means for traversing the plate, means for intermittently moving the plate longitudinally through the machine, and driving means for operating the said means in coöordination,—two guide surfaces arranged on one side of the machine, means connected to the plate and adapted by making contact with the guide surfaces as the plate is moved longitudinally to impart transverse movement to the plate, and auxiliary guide surfaces on the other side of the machine with which the last-mentioned means is adapted to make contact when an overlength plate has to be operated upon; substantially as described.

11. In a punching machine, in combination with punching means, means for intermittently moving the plate longitudinally, and guides,—a hauling carriage and a trailing carriage and a guide bed, each

of said carriages being provided with a pivoted part having lateral jaw-like extensions and runners supported by the bed, a transverse bar for the hauling carriage, a transverse bar for the trailing carriage, said transverse bars being slidable and mounted in said jaws and each being fitted with transversely adjustable plate carrying means and with rollers for engaging with

the guide surfaces; substantially as described.

In witness whereof I have hereunto set my hand in presence of two witnesses.

WILLIAM WOOD.
